(57) **CLAIM**

We claim the ornamental design for a motorcycle swingarm, as shown and described.

DESCRIPTION

FIG. 1 is a top, front, and right side perspective view of a motorcycle swingarm showing our new design;

FIG. 2 is a top, rear, and right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a top, rear, and right side perspective view thereof when installed onto an exemplary motorcycle.

The broken lines in the drawings illustrate an environmental motorcycle and portions of the swingarm that do not form part of the claimed design.
